UNITED STATES PATENT OFFICE

FERDINAND ARMBRUST, OF NORTH PROVIDENCE, RHODE ISLAND, ASSIGNOR TO ARMBRUST CHAIN COMPANY, OF PROVIDENCE, RHODE ISLAND, A CORPORATION OF RHODE ISLAND

BRACELET

Application filed January 16, 1931. Serial No. 509,067.

My invention relates to flexible expansion bracelets of the foldable extension type. In bracelets of this type originally the foldable leaves were enclosed in a container which also housed a spring or elastic element which imparted an elastic or resilient character to the bracelet auxiliary to the extension afforded by the foldable leaves. A housing of such magnitude as required to contain both the leaves and the elastic element was both clumsy and of a character to effectively destroy the visual continuity of the bracelet design. To overcome this it was attempted to interpose in a nearly visually continuous bracelet chain a pair of foldable leaves, backing the chain, and without any housing whatever. But the omission of the housing involved also an abandonment of the elastic or resilient element.

20 An essential object of this invention is to retain all the advantages due to the omission of the original housing, and restore to the bracelet the sacrificed resilient function.

25 A further object is to thoroughly camouflage the presence in the bracelet of the foldable extension, and thus still further impart an unbroken multiple-unit appearance to the bracelet.

30 Additional objects are a minimum thickness of the central portion of the bracelet, sightlessness, and simplicity of operation and construction.

With the above and other objects in view my invention consists in such parts and in such combinations of parts as fall within the scope of the appended claims.

In the accompanying drawings which form a part of this specification,

40 Figure 1 is a front elevation of a watch bracelet embodying my invention with the parts in folded position,

45 Figure 2, a section of an intermediate portion of my bracelet with the parts disposed in wearing position, taken on a line corresponding with 2—2 of Figure 1.

50 Figure 3, a fragmentary front elevation of an intermediate portion of the same in unfolded position, and with the slidable link somewhat expanded,

Figure 4, a longitudinal section of the same taken on line 4—4 of Figure 3, and

Figures 5 and 6, detailed views of a unit link and a tubular link connecting member respectively.

Like reference characters indicate like parts throughout the views.

My bracelet in its present and preferred embodiment includes link strap sections represented generally by 10 and 11, each composed of unit links 13 and, when a wrist watch is employed, terminates in the usual attaching members 15 for connection with a wrist watch.

Each unit link 13 is formed from flat stock and, in this instance, is of rectangular form with a similarly shaped central opening 17, so that each link constitutes a substantially rectangular frame, comprising broad vertical arm portions 18, and reduced cylindrical lateral arm portions 19. The links of each strap section are pivotally connected in series. In this instance each connecting pivoting element consists of a somewhat flattened tubular member 20 loosely embracing the adjacent arms 19 of contiguous links.

Interjected into the body of the chain between the sections 10 and 11 is an extensible connector 23 of the bifold type comprising two longitudinally curved plates or leaves 24 and 25 respectively, provided with forwardly directed flanges 26 and 27 upon their upper and lower portions, and having their outer ends connected by a hinge 29. The rear plate 25 is slightly broader and longer than the front plate 24, so that when they are in closed or overlapped position their flanges 26 and 27 are also in overlapping position. The plates 24 and 25 are provided near their outer ends with rectangular openings 32 and 33 respectively, and near their inner ends, with similarly shaped openings 34 and 35 respectively.

The forward ends of the plates 24 and 25 are respectively forwardly bent to form sleeves 36 and 37, contiguous with each other. The latter loosely encloses one lateral arm 19 of the end unit link 38 of the strap section 10. The sleeve 36 loosely embraces the lateral arm 19 of the unit link 39 next adjacent the last

mentioned link, and constituting the end link of the strap section 11. The extension plates are held face to face by means of a spring finger 41 integral with the plate 25 and embracing the sleeve 36. The latter has an integral lip 43 cut from the material to form a finger or nail piece for separating the extension leaves and the unit links 38 and 39.

The unit link 39 serves as a connector link 10 for a casing 45, open top and bottom, comprising a front wall 46 and a narrower rear wall 47, a wall 48 at one end, and a semi-cylindrical wall or integral sleeve 49 at its other end. The second lateral arm 19 of the link 39 is loose in the tubular end wall 49 of the casing. An open rectangular slide 51 is mounted between the walls 46 and 47 of the casing. Its central rectangular opening 53 forms a cross bar 55 at one end, and a pivot 20 bar 56 at its other end, while the end wall 48 of the casing 45 extends transversely in the opening 53 and forms an abutment for one end of a spring 58 whose opposite end abuts against the cross bar 55. The pivot bar 56 is 25 loose in one of the tubular connectors 20 which also loosely embraces one of the lateral arms 19 of a unit link 60 in the strap link section 11.

When the spring 58 is in expanded position 30 the slide 51 is substantially housed in its casing 45, and by reference to Figures 1 and 2 it will be evident that the casing 45 is disposed symmetrically midway the length of the extensible connector 23 and resting 35 against its front face between the guide flanges thereof. Further, that the opening of the link 39, adjacent one end of the casing, registers with the openings 34 and 35 of the connector 23; while the opening of the link 60 adjacent the other end of the casing, registers with the openings 32 and 33 of the connector 23.

The described opening registrations serve 40 to obscure the presence of the backing extensible connector 23 and thus adds to the visual continuity of the unit links of the strap, or of the strap sections.

It will be further observed that not only is the casing 45 disposed centrally and symmetrically relatively to the extensible member 23 and relatively to the unit links of the entire bracelet, but that it is not attached to nor a constituent part of the extensible section, and is noticeably of minimum thickness 55 and small area.

I claim:-

1. In a bracelet of the type set forth, an extensible connector comprising leaves hingedly connected at their adjacent ends, and sleeves 60 upon their remote ends, means for detachably engaging the sleeves, a series of pivotally connected unit links having an end link loosely attached to one sleeve, a unit link pivotally engaging the second sleeve, a casing carried by the last mentioned unit link and

adapted to abut against the extensible connector, a slide yieldingly mounted in the casing, and a series of unit links pivotally attached to the slide.

2. In a bracelet of the type set forth, an extensible connector comprising a pair of leaves pivotally connected at their adjacent ends, and each provided with a pair of interspaced visual openings disposed at each side of its center, the corresponding openings in one leaf registering with the openings in the other leaf, and sleeves upon their remote ends, means for normally maintaining the leaves in interengagement, a series of open unit links, and tubular connectors engaging adjacent links, an end link of the series being loosely engaged by one of the sleeves, a connecting open unit link adjacent the last mentioned link when the leaves are in closed position pivotally engaged by the 70 second sleeve and having its open portion in registration with one pair of the extensible connector openings, a casing adapted to abut against the central portion of the connector, an open slide in the casing, a compressible 75 spring in the slide pressing against the casing, a tubular connector engaging the slide, an open unit link engaged in the last mentioned tubular connector having its open portion in registration with the second pair of 80 openings in the extensible connector, and a series of open unit links pivotally connected 85 with the last mentioned link.

In testimony whereof I have affixed my 90 signature.

FERDINAND ARMBRUST.
